UNITED STATES PATENT OFFICE.

ALBERT DREWITZ, OF SYRACUSE, NEW YORK.

FASTENER FOR RECEPTACLE-COVERS.

1,241,831.

Specification of Letters Patent.

Patented Oct. 2, 1917.

Application filed May 16, 1916. Serial No. 97,842.

To all whom it may concern:

Be it known that I, ALBERT DREWITZ, a citizen of the United States, residing at Syracuse, in the county of Onondaga and State of New York, have invented certain useful Improvements in Fasteners for Receptacle-Covers, of which the following is a specification, reference being had therein to the accompanying drawing.

10 This invention relates to improvements in receptacle closures, one object of the invention being the provision of a closure and locking device therefor, which is bodily removable with the closure and which will 15 automatically adjust itself to secure the closure in position as a locking screw is actuated.

A further object of this invention is the provision of a device of this character in 20 which radially slideable arms are employed to grip the periphery of the can or receptacle and also the periphery of the closure and coöperate with a single screw operated means and a projection upon the closure to 25 firmly grip and hold the closure upon the receptacle.

A still further object of this invention is the provision of a device of this character which is simple, durable and inexpensive in 30 construction, and which is thoroughly efficient and practical in use.

In the accompanying drawings:—

Figure 1 is a side elevation of a receptacle provided with the present closure.

35 Fig. 2 is a top plan view thereof.

Fig. 3 is a cross section taken on line 3—3 of Fig. 2 with the arms in the position they assume previous to being actuated upon and act as clamps.

40 Fig. 4 is a similar view showing the arms clamped.

Referring to the drawings, the numeral 5 designates the receptacle which may be of any ware or material desired, and having 45 adjacent to the mouth thereof the outstanding flange or rim 6.

The cover or closure 7 for the receptacle is made in the form of a disk having a rim 8

between which latter and the rim 6 is received the gasket 9.

Carried by the cover centrally thereof is a screw 10 having the short cylindrical sleeve 11 thereabout, a coil spring 12 being mounted upon said sleeve and normally exerting an outward tension.

50 Mounted for sliding movement upon the screw are the two concavo-convex disks 13 and 14, the disk 14 being provided with the radial slots 15 for the reception of the lugs or pins 16 carried by the radially movable clamping arms or levers 17.

55 Each of these arms is provided with the hooked terminal 18 for projection beyond the periphery of the flange 6 and the cover or closure 7, while carried by the screw beyond the outer disk 14 is a thumb nut 20. Thus the spring normally holds the disks outwardly while the thumb nut operates in opposition to the spring to press the inner ends of the clamping bars downwardly so 70 the intermediate portion thereof will bear upon the annular projection 21 carried by the closure and thus force the hooked terminals upwardly exerting pressure upon the underside of the flange 6, while pressure is 75 exerted upon the closure by the action of the arms upon the annular projection.

75 From the foregoing description, it is evident that the clamping arms may be readily adjusted and with their hooked ends disposed as shown in Fig. 3 so that by operating the thumb nut, the two disks will be moved downwardly carrying with them the inner ends of the arms and thus producing with the co-action of the hooked ends of the 80 arms and the annular projection of the closure, the aforementioned action.

To facilitate the opening of the cover, the central thumb nut is released, so that the screw can be pushed downwardly, thereby 90 admitting air to the receptacle so that the cover can be lifted without any appreciable effort.

What I claim as new is:—

95 A fastener adapted to be used with a receptacle having an outstanding flange at

the top thereof and a closure having a gasket retaining arm fitted on the flange including a screw carried concentrically of the closure, two concavo-convex clamping disks 5 mounted upon the screw, a spring for normally holding the disks outwardly, a plurality of levers having their inner ends slidably connected between the disks, hooks

formed on the outer ends of the levers and embracing the periphery of the flange and 10 closure, a fulcrumming member for each lever carried by the closure, and a thumb nut mounted upon said screw for compressing the disks and the inner ends of said levers.

In testimony whereof I affix my signature.

ALBERT DREWITZ.
